GRILLE FOR A TRACTOR

Leo J. Lorenz, Farmington, and Wilford E. Bean, Southfield, Mich., assignors to Massey-Ferguson Inc., Detroit, Mich.

Filed Aug. 21, 1972, Ser. No. 282,188

Term of patent 14 years

Int. Cl. D12—09

U.S. Cl. D40—5

Fig. 1

FIG. 1 is a front elevational view of a grille for a tractor embodying our new design;

FIG. 2 is a right side elevational view thereof; and

FIG. 3 is a left side elevational view thereof.

We claim:

The ornamental design for a grille for a tractor, substantially as shown.
